UNITED STATES PATENT OFFICE.

GUSTAV FUCHS, OF CHICAGO, ILLINOIS.

DESIGN FOR AN ADVERTISING-STATUE.

SPECIFICATION forming part of Design No. 22,792, dated September 19, 1893.

Application filed May 11, 1893. Serial No. 473,881. Term of patent 14 years.

To all whom it may concern:

Be it known that I, GUSTAV FUCHS, a citizen of the United States, residing at Chicago, in the county of Cook and State of Illinois, 5 have invented a novel Design for an Advertising-Statue; and I do hereby declare the following to be a full, clear, and exact description of the invention.

My design consists of a novel configuration 10 and ornamentation of an advertising statue, as hereinafter set forth, and shown in the accompanying drawing.

Said drawing is a perspective view of a statue made in accordance with my invention.

15 The said drawing shows the representation of a St. Bernard dog in a standing position with the representation of a small keg or barrel fastened to his collar, and the representation of a blanket strapped to his back. The dog is represented as standing upon a pedestal or base, the sides of which are plain. The effect produced is novel and ornamental and the arrangement is effective, agreeable and pleasing to the eye. 20

I claim as my invention—

25 The design for a statue consisting of the representation of a St. Bernard dog with a collar, a small keg or barrel fastened to the collar, a blanket strapped upon the back of the dog, and a plain base or pedestal upon which the dog is represented as standing, substantially as shown and described.

In testimony whereof I affix my signature in presence of two witnesses.

GUSTAV FUCHS.
